UNITED STATES PATENT OFFICE.

LAURITZ W. ANDERSEN, OF WATERBURY, CONNECTICUT, ASSIGNOR TO THE PLUME & ATWOOD MFG. CO., OF WATERBURY, CONNECTICUT, A CORPORATION OF CONNECTICUT.

SAFETY APPLIANCE FOR SCREWLESS HOLDERS.

1,114,571.

Specification of Letters Patent. Patented Oct. 20, 1914.

Application filed June 3, 1914. Serial No. 842,753.

To all whom it may concern:

Be it known that I, LAURITZ W. ANDERSEN, a citizen of the United States, residing at Waterbury, in the county of New Haven 5 and the State of Connecticut, have invented a new and useful Improvement in Safety Appliances for Screwless Holders, of which the following is a specification.

This invention relates generally to electric 10 light fixtures and more particularly to a safety attachment adapted for use in connection with the screwless socket cover and holder patented to me May 12, 1914, No. 1,096,523.

15 A holder of this kind is particularly adapted for use in connection with globes and other forms of shades, and the object of the present invention is to provide a holding means for locking the interior shade engag- 20 ing means while the exterior shade engag- ing means is being released and elevated, thereby avoiding the necessity of holding the shade or globe in one hand while the exterior shade holding means is being released.

25 With this object in view my invention consists essentially in the employment of a catch attached to the socket receiving shell which catch is adapted to engage the interior shade supporting means which are 30 hinged to the said shell and are adapted to be inserted into the mouth of the shade to engage the interior thereof, the exterior of said shade being engaged by an outer shell connected to said inner shell and which also 35 serves to lock the hinged wings; it being understood that said wings are collapsed or contracted for the purpose of inserting the same into the mouth of the shade or globe to be supported.

40 The invention consists also in certain details of construction hereinafter fully described and pointed out in the claims.

In the drawings forming a part of this specification: Figure 1 is a view showing the 45 practical application of my invention, the globe or shade being securely fastened to the combined screwless socket cover and holder. Fig. 2 is a view showing the outer shell elevated and the globe, in dotted lines, 50 supported upon the hinged wings, said wings being held in place by means of my improved safety appliance. Fig. 3 is a similar view showing the wings released from the safety appliance and collapsed for in-

sertion into or withdrawal from the mouth 55 of the globe or shade. Fig. 4 is a vertical sectional view of my device, the socket being shown in elevation. Fig. 5 is a vertical sectional view illustrating in detail the safety appliance. Fig. 6 is a horizontal sectional 60 view illustrating said appliance, and Fig. 7 is a detail perspective view illustrating one of the hinged wings.

In the drawings A indicates a globe or shade, B the incandescent lamp, and C the 65 socket all being of the usual construction, the socket C being connected to a conductor pipe D, and mounted upon or connected to this pipe D is the inner shell E which is adapted to serve as a socket holder or cover 70 and is preferably provided with threads E¹ and also with an annular shoulder E².

An outer shell F is connected to the inner shell E through the medium of the threads E¹ and this outer shell is movable upon the 75 inner one for the purpose of engaging the exterior of the shade or globe A and also for the purpose of securely locking the wings or members G, which are hinged or pivotally connected to the lower end of the 80 inner shell said hinge or pivotal connection being intermediate the ends of the wings and accomplished by means of lugs E³ projecting through slots G³ cut in the wings. The lower ends of these wings are curved 85 outwardly as shown at G¹ in order to engage the interior of the shade or globe as shown in Figs. 2 and 4, and the upper ends of the wings are formed with inwardly projecting flanges G² which are adapted to be brought 90 into engagement with the annular shoulder E² when the said wings are spread to engage and support the shade or globe. When the outer shell F is screwed down to engage 95 the exterior of the globe it also engages the upper ends of the wings and holds them firmly locked. For the purpose of maintaining these wings in their spread and supporting positions while the outer shell is being released and raised I employ a safety 100 appliance for maintaining these wings in this position, said safety appliance preferably consisting of a piece of spring metal H attached to the interior of the inner shell and extending downwardly to the lower end 105 of the shell which at that point is cut away to afford room for a knob or button H¹ carried at the end of the spring plate H. This

plate H is provided with beveled lugs or noses I which project through openings in the inner shell and are adapted to engage the openings K produced in the adjacent 5 ends of the wings, as most clearly shown in Figs. 2, 6 and 7. By reference to these figures it will be readily understood that when the wings are spread or expanded so as to engage the interior of the shade or globe the 10 apertured ends will ride over the beveled lugs or noses which will spring out into engagement with the apertures K as soon as the wings have reached their limit of expansion and the elasticity of the spring plate 15 H will hold these parts in engagement and the globe or shade will be supported, irrespective of the position of the outer shell F and consequently both hands can be employed for the manipulation of said outer shell. When it is desired to completely release the wings the knob or button is pushed inwardly, withdrawing the lugs from the wings, and they can then be collapsed or folded into the position indicated in Fig. 3. 20 It will thus be seen that I provide a simple and efficient safety appliance for use in connection with the screwless type of shade holder and by means of which the free use of both hands can be had at all times. 25 30 What I claim is:

1. A device of the kind described comprising a shell adapted to receive a socket, means connected thereto for engaging the interior of a shade, means carried by said

shell for holding said shade engaging means 35 in contact with the shade together with means attachable to the shell and adapted to lock said interior means in position and also engage the exterior of the shade.

2. A device of the kind described comprising a shell and means connected thereto for engaging the interior of a shade, means attachable to said shell and adapted to engage the exterior of the shade, together with means carried by said shell for holding the 45 interior shade engaging means independent of the exterior means.

3. A device of the kind described comprising a shell, wings attached to the end of said shell and a catch attached to said shell 50 and adapted to engage said wings, and an outer shell attachable to the inner shell.

4. A device of the kind described comprising an inner shell, wings hinged thereto, a spring catch attached to said shell and 55 adapted to engage said wings, and an outer shell attachable to said inner shell.

5. A device of the kind described comprising an inner shell, wings hinged to said shell, a spring plate attached to said shell, 60 and provided with lugs adapted to engage apertures in said wings, and an outer shell attachable to said inner shell as set forth.

LAURITZ W. ANDERSEN.
